WILLIAM HALL, OF NORTH ADAMS, MASSACHUSETTS.

Letters Patent No. 89,041, dated April 20, 1869.

IMPROVED MOP-WRINGER.

The Schedule referred to in these Letters Patent and making part of the same.

To all whom it may concern:

Be it known that I, WILLIAM HALL, of North Adams, in the county of Berkshire, and State of Massachusetts, have invented certain new and useful Improvements in Mop-Wringers, of which the following is a full, clear, and exact description, reference being had to the accompanying drawings, which make part of this specification, and in which—

Figure 1 represents a vertical, longitudinal section of my improved mop-wringer, and

Figure 2, a plan or top view of the same.

The object of my invention is to provide a simple and convenient device by which the superfluous water may be wrung from a mop, for the purpose of facilitating the operation of washing floors, wood-work, windows, &c., to which end my improvements consist in providing a pail, which is secured upon a portable platform, with a horizontal strainer, and segmental press-plate for wringing the mop, the press-plate being connected by draw-rods, to a transverse rod, moving in stationary guides attached to the pail, to which motion is imparted by means of bent levers, pivoted to the guides, and connected to it by pivoted arms.

In the accompanying drawings, which show a convenient arrangement of parts for carrying out the object of my invention—

A represents a pail, or bucket, of ordinary construction, which is secured upon a portable platform, A', which gives it a firm base, and prevents liability of upsetting when in use.

A horizontal strainer, a, provided with a number of holes, for the passage of the water which is wrung from the mop, is attached to the inside of the pail, at a convenient distance from its top, leaving sufficient room for the mop to pass it to be inserted into the water below.

A segmental press-plate, B, moves horizontally upon the top of the strainer, and is connected by the draw-rods b, to a transverse rod, C, the ends of which move

in slots e, formed in the stationary guides E, which are secured to the pail A and to standards F, upon the platform.

Stiffness is imparted to the standards F by the transverse brace f.

Bent levers, D, are pivoted at one end to the guides E, and at their angles to the arms C', the opposite ends of which are pivoted to the rod C.

The levers D are connected at their upper ends by the handle d.

G represents the handle of the pail.

The parts being in the position shown in the drawings, and the pail partially filled with water, by depressing the upper ends of the levers D, by means of the handle d, the arms C' cause the rod C to move in the slots e, toward the standards F, drawing with it the press-plate B.

The mop having been dipped into the water in the pail, is rested upon the strainer a, and the superfluous water is wrung from it by its compression between the inside of the pail and the press-plate B, when the latter is drawn up to it, as described, by the action of the levers D, and pivoted arms C'.

The superfluous water runs back into the pail, through the holes in the strainer, and the mop is thus expeditiously and thoroughly wrung, obviating the spilling of water on the outside of the pail, which will always happen when a mop is wrung by pressure against the edge thereof, as is ordinarily the case.

Having thus fully described my invention,

I claim—

In combination with the segmental press-plate B, the bent lever D, pivoted arm C', rod C, slotted guides E, draw-rods b, all arranged and operating substantially as and for the purposes set forth.

WILLIAM HALL.
